ALBERT E. JOHNSON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-FITTING MACHINE.

1,349,723.

Specification of Letters Patent. Patented Aug. 17, 1920.

Application filed May 8, 1916. Serial No. 96,170.

To all whom it may concern:

Be it known that I, ALBERT E. JOHNSON, a citizen of the United States, residing at Beverly, in the county of Essex and State 5 of Massachusetts, have invented certain new and useful Improvements in Sole-Fitting Machines; and I do hereby declare the following to be a full, clear, and exact description of the invention, such as will enable 10 others skilled in the art to which it appertains to make and use the same.

This invention relates to sole fitting machines and more particularly to channeling machines which are used to channel, 15 groove, shoulder or otherwise operate on the margin of a sole blank to prepare it for attachment to the other parts of a shoe.

The invention is particularly concerned with the machine known commercially as 20 the Economy insole channeling machine, and it aims to improve the feeding mechanism of this machine with a view particularly to reducing the skill and care required of the operator; to devise a more 25 satisfactory mechanism for registering or indicating the quantity of work done on the machine; to improve the lip cutting or slashing mechanisms often used in these 30 machines; and generally to improve the construction and operation of machines of this type. The general construction of the machine above designated is shown in the Letters Patent of the United States to William C. Meyer, No. 984,773, granted February 21, 1911. While the present invention 35 is directed particularly to the improvement of this machine, those skilled in the art will recognize that the various features of the invention are also applicable to other machines for performing analogous operations.

To the accomplishment of these objects and such others as may be hereinafter described, the invention resides in certain combinations and arrangements of parts, 45 the construction and functions of which will be described hereinafter with the aid of the accompanying drawings, which show the preferred embodiment of the invention.

Referring now to the drawings, 50 Figure 1 is an elevation of the left-hand end of the channeling machine;

Fig. 2 is a cross-sectional view on the line

2-2 Fig. 1, showing a detail of construction;

Fig. 3 is an elevation of the back of the 55 machine shown in Fig. 1;

Fig. 4 is a horizontal, cross sectional view taken substantially on the plane indicated by line 4-4, Fig. 3;

Fig. 5 is an elevation partly in vertical 60 section showing a detail of construction of the lip slashing mechanism;

Fig. 6 is an end elevation of the indicator mechanism with the cover removed;

Fig. 7 is a longitudinal, sectional view 65 in elevation, illustrating the lip slashing mechanism in particular, certain parts of the machine with which the present invention is not especially concerned being omitted;

Fig. 8 is a side elevation of the sole feed- 70 ing plate;

Fig. 9 is a cross-sectional view on the line 9-9, Fig. 7; and

Fig. 10 is a vertical, cross-sectional view 75 of the indicator.

The main constructional features of the illustrated embodiment of the invention resemble very closely those of the machine shown in the Meyer Patent No. 984,773, 80 above designated. The machine comprises a channeling knife 2 and an edge slitting knife 4, which cut and turn up the usual flaps or lips of a welt insole; a hammer 6 which sets these lips in their upturned position; a work supporting table 8 on which the sole is mounted while it is being channeled; a presser foot 10 which bears on the sole and presses it against the table 8 adjacent to the point of operation of the knives 90 2 and 4; and a four-motion feed plate 12 which engages the upper face of the sole and feeds it over the table 8 against the drag knives 2 and 4.

The knives 2 and 4, the hammer 6, the 95 table 8, and the presser foot 10 are all supported and operated substantially as shown in said Meyer patent, and reference should be made to this patent for a detailed description thereof. For the purposes of the 100 present invention it is sufficient to state that the work supporting table 8 is mounted for vertical movement relatively to the channeling tools to permit the insertion or re-

removal of a sole between it and the tools. The two knives 2 and 4 and the presser foot 10 are all mounted rigidly on a knife carrier 14 which is yieldingly pressed toward the table 8 by means of a spring 15 that permits these devices to yield away from the table to accommodate variations in the thickness of the sole.

The lower end of the presser foot 10 bears on the sole, as shown in Fig. 7, and since the knives 2 and 4 project a fixed distance below the end of the presser foot, this member determines the depth of cut of the knives. This presser foot (see Fig. 7) as in the construction shown in the patent, has a shank 16 provided with beveled edges which are received in suitable ways, one formed in a presser foot block 17 which is bolted, as usual, to the channel knife carrier 14, and the other in a gib 18 which is clamped to the block 17 by a bolt 19.

In order to enable the operative quickly to effect a fine adjustment of the presser foot 10 relatively to the knives 2 and 4, a pin 20 (Fig. 9) is rotatably mounted in the presser foot block 17 and has an eccentric projection 21 which extends into a horizontal slot formed in the shank 16 of the presser foot. A screw 22 holds this pin in its operative position. The end of the eccentric projection 21 has two holes drilled therethrough at right angles to each other to receive a pin or nail by means of which the eccentric pin may be turned. It is obvious that if the clamping bolt 19 is loosened and the pin 20 is turned about its axis, the eccentric projection 21 will move the presser foot 10 up or down relatively to its supporting block 17, and consequently will adjust this presser foot up or down relatively to the channeling tools 2 and 4. When the desired adjustment has been effected the bolt 19 is set up, thus clamping the presser foot securely in its desired position.

As above indicated, the feed plate 12 is given a feeding movement that advances the sole 8 from right to left, as the parts seen in Fig. 1, and carries it past the tools 2 and 4. This motion is the same as that imparted to the corresponding feed plate of the machine shown in said Meyer patent; but a novel mechanism is provided by this invention for producing this movement. Furthermore, in the machine of said patent the feeding movement is fixed or uniform at all times. It will be readily understood by those skilled in the art that it is sometimes desirable to reduce the length of stroke of the feeding device as, for instance, when channeling around the more sharply curved portions of the margin of an insole. For example, it is difficult to make the turn at a sharp toe if the work is being advanced at the maximum speed which can be used successfully along the straighter portions of

the margin of the sole. The present invention, therefore, provides a construction by which the length of feed step can be reduced whenever the workman finds it advantageous to do so.

As best shown in Fig. 1, the feed plate 12 is clamped in a holder formed at the lower end of a rod 24, the plate 12 being provided with a dovetail projection which fits into a corresponding seat formed for it in the 75 clamping members. This rod is guided in the lower arm of a yoke 25 and in a sleeve 26 which slides freely through the upper arm of the yoke. A spring 28 is seated at its opposite ends on two collars formed, respectively, on the rod 24 and the sleeve 26. The upper end of the rod 24 extends loosely through a sleeve 29, which is positioned between a pair of nuts 30 on the rod 24 and another pair of nuts 31 on the sleeve 26, and this sleeve is pivotally mounted on the free end of an arm 32 fixed to a rock shaft 34 that is mounted in suitable bearings in the upper part of the machine frame. Another arm 35 also fixed to the rock shaft 34, and preferably parallel to the arm 24, is pivotally connected to the upper end of a depending cam follower 36 that incloses a cam 38 (dotted lines Fig. 1) mounted fast on the main shaft 40 of the machine. It is 95 obvious that as this cam follower 36 is reciprocated up and down by the movement of the cam 38, it will produce an up and down movement of the sleeve 29. The upward movement of this sleeve is transmitted 100 through the nuts 30 and rod 24 to the feed plate 12, thus lifting it positively away from the work; while the downward movement of the sleeve 29 is transmitted yieldingly to the plate 12 through the nuts 31, sleeve 26, 105 spring 28 and rod 24.

The horizontal reciprocating movement given to the feed plate 12 is produced by an eccentric pin 42, projecting from the end of the shaft 40, and rotatably mounted in an 110 eccentric block 43 which slides in a slot formed in the yoke 25. The right-hand end of this slot (Fig. 1) is closed by a plate 44 and a spring 45 (Fig. 2) located between the block 43 and the plate 44 tends to maintain 115 this block at the opposite end of the slot. Ordinarily, however, the full horizontal component of the eccentric movement of the pin 42 will be transmitted to the yoke 25, one stroke of course being transmitted directly 120 by the engagement of the block 43 with one end of the slot in the yoke 25 and the opposite stroke being transmitted to the yoke through the spring 45. The horizontal movement produced by this eccentric pin 42 125 and the vertical movement produced by the cam 38 are timed to effect the desired four-motion feeding movement of the plate 12.

The shortening of the feeding movement above referred to, is produced by limiting 130

the range of the movement of the yoke 25 which is transmitted to it through the spring 45. For this purpose a stop screw 48 is adjustably mounted in the free end of an arm 49 (Fig. 1) which is pivoted on the machine frame and normally is held in a raised position by means of a spring 50; but the arm may be depressed by operating a foot treadle (not shown). The connection 10 between the arm 49 and foot treadle comprises a rod, or bent wire, 51 (dotted lines Fig. 3) connecting the free end of the arm to the forward end of a lever 151 pivoted on the frame and depending from the lever 151 is a cord or chain attached to the treadle. When the lever 49 is swung downwardly, the end of the stop screw 48 is moved into the path of movement of a hardened plate 52 carried by the yoke 25, and the engagement 20 of this plate with the stop screw stops the movement of the yoke 25 before it has completed its backward stroke. Inasmuch as this stroke is transmitted to the yoke through the spring 45, and since the eccentric pin 42 moves in a fixed path, the part of the movement of the eccentric pin which otherwise would complete the stroke of the yoke, is taken up in compressing the spring 45. As soon as the treadle is released the spring 50 30 withdraws the stop 48 from the path of movement of the plate 52 (a pin 54 in the frame limiting this movement of the stop) and the yoke is then free to make its full horizontal stroke. The ability of the workman to change the length of the stroke of the feed plate 12 quickly whenever desired, is a great convenience in guiding any character of work having different angles.

The presser foot 10 as clearly shown in Figs. 4 and 7 is slotted to straddle the forward end of the feed plate 12. The knives 2 and 4 lie immediately behind the presser foot 10 so that one end of the feed plate passes between these knives on its forward stroke and exerts its feeding effort on the sole at points very close to the point at which the knives resist the advancing movement of the work. The part of the presser foot that bears on the extreme marginal portion of the sole 8 (see Fig. 4) lies just in front of the edge gage 56 which serves to guide the sole relatively to the tools while the channeling operation is being performed. This edge gage is moved in and out, as the channeling operation progresses around the margin of the insole, by means of a mechanism exactly like that disclosed in the Meyer patent above designated. When the edge gage is moved toward the tools there is sometimes a tendency for the extreme marginal portion of the insole to curl up as it is fed forward against the edge gage, and thus to interfere with the proper guiding of the sole relatively to the knives 2 and 4. In 50 order to overcome this difficulty the feed

plate 12 is provided with a lateral extension 57 (see Figs. 4 and 8) having a sole engaging face lying in the same plane as the corresponding face of the feeding device. This extension bears on the extreme marginal portion of the sole just in front of the edge gage 56, and serves to press the margin of the sole firmly against the sole supporting face of the table 8. Since a part of the presser foot 10 also bears on the extreme margin 70 of the sole just behind the edge gage 56, this part of the presser foot cooperates with the extension 57 to hold that part of an insole which at any instant bears against the edge gage 56, flat against the table 8 and thus 80 prevents any objectionable curling up of the sole.

In the machine illustrated the edge gage 56 is shown as provided with a chamfering knife which is described and claimed in my 85 copending application, Ser. No. 83,053, filed March 9, 1916, patented December 5, 1916, No. 1,207,409 but this attachment may or may not be used, as desired.

It is often desirable to cut or slash transversely one or both of the lips or flaps formed by the knives 2 and 4 for the purpose of facilitating the turning of these lips upwardly. To this end a knife 60 (see Figs. 4 and 7) is mounted close beside the presser 90 foot 10 where the stock is held firmly to the table, preferably, although not necessarily, between this device and the knives 2 and 4, so that it will cut into or slash the stock just before the knives 2 and 4 form the lips. In 100 other words, this knife operates in advance of the lip forming tool to make transverse slashes in that portion of the stock lying in the path that the tool will take in the sole, so that when the lip is formed it will be provided with transverse slashes in the desired manner. The knife shown in dotted lines (Fig. 7) is shaped to slash both the lips formed by the knives 2 and 4, but it does not cut or slash the "between substance." Obviously, however, the knife may be shaped to cut only one of the lips if desired. By locating the knife close beside the presser foot 110 the depth of its cut can be accurately determined, since the presser foot holds the sole firmly against the table 8 and the knife 60 cuts to a fixed point above the table. The depth of cut should be not greater than the thickness of the stock cut by the tool so as not to weaken the body of the insole.

The knife 60 is secured in a holder 61 by a clamping bolt 62, the holder being grooved, as shown in Fig. 4, and the knife being slotted as shown in Fig. 7, to permit a vertical adjustment of the knife relatively to its 125 holder. The holder consists of a bell crank lever fulcrumed at 63 and having an upright arm 64. A spring 65, connected at one end to the machine frame and at its opposite end to the holder 61, maintains the 130

knife 60 normally in a raised position where it is inoperative to cut the sole.

A power driven mechanism is provided to give the knife its cutting movement, and this mechanism is controlled by the workman through the hand lever 66 by which the adjusting movement of the edge gage 56 is effected. The knife operating mechanism comprises an arm 68, pivoted to the free end 10 of the bell crank lever arm 64, and projecting through a slot formed in the machine frame so that it can be swung either into or out of position to be engaged by the head 70 of a stud that is inserted in the front face of 15 the cam disk 71, found also in said Meyer patent, mounted fast on the shaft 40. The stud 70 acts as a tappet cam for operating the knife 60 as will now be described. When the arm 68 is in the position in which it appears 20 in full lines in Fig. 7, it is completely out of the path of movement of the pin 70, and the slashing mechanism, therefore, is inoperative at this time; but when this arm is swung up into the position in which it is 25 shown in dotted lines in Fig. 7, it lies in the path of the cam 70, and will be struck by this cam once in each rotation of the shaft 40. Each blow thus delivered to the arm 65 swings the knife holder 61 downward about 30 its pivot 63 causing it to quickly approach and form a slash in that portion of the margin of the sole which is below it. The cutting operation is instantaneous as the knife, of course, is immediately withdrawn from 35 the stock by the spring 65.

The controlling mechanism for causing an operation of the knife 60 includes a lever 72 pivoted on a bolt 73 (see Fig. 4) and having a forked end that embraces the arm 68 and 40 serves to swing this arm either into or out of the path of movement of the cam 70. The opposite end of the lever 72 is pivoted to the upper end of a rod 74 which is mounted to slide vertically through a stationary 45 guide 75 (see Fig. 5) on the machine frame, and through a bracket 76 which is movable with the work table 8 relatively to the rod 74 and forms part of the support for the edge gage adjusting mechanism. A spring 50 78 encircling the rod 74, and bearing against a collar 79 secured thereto, tends to raise the rod and thus to swing the lever 72 into such a position that it will hold the arm 68 in its 55 inoperative position in which it appears in full line in Fig. 7. For the purpose of depressing the rod 74 against the influence of the spring 78, a curved lever 80 (Figs. 4 and 5) is connected with the rod 74 through a clutch so that it is free to move up and 60 down with the bracket 76 relatively to the rod except when it is moved to throw the slashing mechanism into operation. As best shown in Fig. 5, this lever 80 is pivoted at 65 81 in a head 82, having an integral sleeve 83 surrounding the rod 74 extending upwardly

therefrom through an aperture formed for it in the bracket 76. A spring 84 encircling this sleeve bears at one end on a collar 85, which is clamped to the sleeve, and at its other end on the upper side of the bracket 76 so that it tends to maintain the head 82 in contact with the lower side of the bracket. When the lever 80 is depressed, it first swings about its pivot 81 in a clockwise direction (as seen in Fig. 5), at which time a sharp 75 edge 87 formed on the upper end of the lever bites into the side of the rod 74 and causes the rod thereafter to move downward with the lever. A suitably connected spring 88 tends to swing the lever 80 about its pivot 80 81 in a direction to hold the lever free from the rod.

As clearly explained in the Meyer patent, above designated, the lever 66 must be swung about the axis of the disk 67 in order to 85 effect an adjusting movement of the edge gage 56. A latching mechanism, however, is provided to hold the lever 66 in any adjusted position, and before this lever can be swung to change the adjustment of the edge 90 gage, it must be depressed to unlatch it, such movement being effected against the tension of a spring 69 (see Fig. 1). A change in the adjustment of the edge gage is required as the channeling operation progresses along 95 the part of the insole near the junction of the shank and fore part, and it is usually while this portion of the sole is being channeled that it is desirable to cut or slash one or both of the lips formed by the tools 2 100 and 4. Advantage is taken of this condition by placing the slashing mechanism under the control of the edge gage adjusting mechanism so that a single lever will control both the edge gage and also the slashing mechanism. 105 It is for this reason that the lever 80 lies just under the lever 66, and that it is curved so as to extend parallel to the path of the swinging movement of the lever 66. The parts are so designed that when the 110 lever 66 is depressed to unlatch it, preparatory to changing the adjustment of the edge gage, it may engage the lever 80 but will not move it down far enough to cause it to grip the rod 74 and operate the slashing 115 mechanism. A further depression of the lever 66, however, will initiate the operation of the slashing mechanism. This mechanism will then continue to operate until the lever 66 again releases the lever 80 to the 120 influence of the spring 88. The downward movement of the lever 66 operates (as will be clear from Fig. 5) first, to swing the lever 80 about its pivot 81 and cause it to grip the rod 74, and thereafter, as it is moved 125 farther downward, to carry the rod 74 down with it, thus tipping the lever 72 far enough to move the arm 68 into the path of rotation of the cam 70 with the result already described. As soon as the pressure thus ap- 130

plied to the lever 80 is removed, the spring 88 swings the lever in a direction to release the rod 74, whereupon the spring 78 raises this rod thus swinging the arm 68 again out of the path of movement of the cam 70 and stopping the operation of the slashing knife. The spring 84 also returns the head 82, and with it the lever 80, to their normal positions. A small pin 90 projecting from the head 82 through an aperture in the bracket 76 guides the head in its up and down movements.

It is obvious that if it is desired to slash the lip of the insole at some period when it is not desired to change the adjustment of the edge gage 56, as for instance when channelling around the toe, it is merely necessary to depress the edge gage operating lever 66. This novel controlling mechanism, however, is highly advantageous in enabling the operative to control, through a single lever, both the adjustment of the edge gage and also the operation of the slashing knife; and to operate either one of these parts, or both of them simultaneously, as may be desired.

The slashing mechanism of course is used chiefly when the machine is operating along the more sharply curved margin of a sole near the junction of the shank and forepart, and around the toe. At other times it is preferable to avoid slashing the lip; and the number of slashes required for any curve depend, of course, on the radius and length of the curve. The controlling mechanism provided by this invention enables the workman to throw the slashing mechanism into and out of operation at will and to make as few or many cuts in any portion of the lip material as may be desired.

Machines of this character ordinarily are put out on a royalty basis and it is a common custom to measure this royalty by the number of revolutions that the machines make, in producing a pair of soles, an indicator being provided to register the turns or revolutions of the main shaft of the machine. While this practice is fairly accurate still a careless operator may allow his machine to run idly, thus indicating a larger quantity of work done than actually has been performed. To obviate this disadvantage it is the better practice to register the number of pairs of soles passed through the machine. The illustrated machine, therefore, is equipped with a registering or indicating device which is operated only by a movement of the work supporting table 8 of sufficient extent to insert or remove a sole. The indicator 92 may be of any suitable construction and may be mounted in any convenient position on the machine but is here shown as secured to the top of the machine frame at the right. The operating mechanism for the indicator consists of a

modified bell crank lever 93 (see dotted lines Fig. 3) fulcrumed at 94 inside the frame and having a ball end 95 engaging a slot formed in the vertically movable slide which forms the shank of the table 8 and, therefore, moves with it. This lever extends from front to back of the machine and is pivotally connected at its rear end to a long upright rod 96 that extends within the frame and into the casing of the indicator. The upper end of this rod is shaped to engage and actuate the toothed registering mechanism operating wheel 97 with which indicators of this character usually are provided. A spring 98 (see Fig. 6) acts on the rod 96 to press it against the periphery of the wheel 97.

As fully explained in said Meyer patent the work supporting table 8 is rigidly held in its upper or operative position while the machine is channelling a sole, the tools that operate on the sole being supported to yield, as required, to variations in the thickness of the work. Only a relatively small downward movement of the table is actually necessary to permit the removal or introduction of the work, although a considerable movement is ordinarily given to it for this purpose. Accordingly, the parts 93 to 97 that operate the indicator are arranged to transmit a registering movement to the indicator during the first part of the downward movement of the table 8, and a continuation of its downward movement does not further affect the indicator. For this purpose the upper end of the rod 96 is so shaped that when it is in its lowered position, and the table 8 is raised, the end of the rod will lie just under the edge of the next tooth with which it is to engage (see Fig. 6); and when the table is depressed even a fraction of an inch, the rod 96 will be moved upward far enough to cause its end to engage said tooth and move the wheel 97 ahead, one tooth. The rod, however, operates so nearly on a tangent to the wheel 97 that as soon as it has performed this operation the next succeeding tooth will force the rod 96 to the right in Fig. 6 and out of engagement with the tooth which it has just advanced. Thereafter the rod 96 will continue to move upwardly, in substantially a straight line in response to a continued depression of the work table. Such a movement obviously will not affect the indicator, it being necessary for the rod to return again to its lowermost position before it can again transmit a movement to the indicator wheel. As shown in Fig. 6 sufficient teeth are provided on the indicator wheel 97 to provide for an operation of the registering mechanism only at each second operation of the rod 96, that is, it registers pairs of soles. Suitable friction pawls or equivalent de-

vices are, of course provided to prevent the accidental movement of the toothed wheel 97. The indicator obviously may be designed to indicate the number of single soles 5 operated upon instead of pairs of soles, as may be found convenient.

While the invention has been illustrated as embodied in a machine for preparing insoles it is not in its broadest aspect limited 10 to such a machine, but may be used in machines for performing other analogous operations. The invention also is not, in general, limited to the details of construction and operation of the specific embodiment 15 herein shown and described.

What is claimed as new, is:—

1. In a machine of the character described, the combination with means for supporting and feeding a shoe sole and a 20 lip forming tool, of a knife arranged to slash the lip material transversely, means for throwing said knife into and out of operation at will during the continued operation of said feeding means, and means for 25 variably determining the position of the sole transversely relative to said knife.

2. In a machine of the character described, the combination with means for supporting and feeding a shoe sole and a 30 lip forming tool, of a knife operative in advance of said tool to slash transversely the stock in the path of said tool, and means for throwing said knife into and out of operation at will during the continued 35 operation of said feeding means.

3. In a machine of the character described, the combination with means for supporting and feeding a shoe sole and a 40 tool operative to make a lip cut in a sole so supported and fed, of a knife coöperating with said tool to form a transversely slashed lip, an edge gage for guiding the sole relatively to said tool, means for adjusting said edge gage, and means controlled 45 through said edge gage adjusting means for rendering said knife operative or inoperative at the will of the operative.

4. A sole fitting machine having, in combination, means for supporting and feeding a 50 shoe sole, a tool arranged to operate on the marginal portion of a sole so supported and fed, an edge gage for guiding the sole relatively to said tool, means for adjusting said edge gage including a manually operated device, a power driven knife arranged to slash the stock adjacent to the point of operation of said tool, and controlling means for said knife arranged to be operated at the will of the operative through a movement of said 55 device.

5. A sole fitting machine having, in combination, means for supporting and feeding a shoe sole, a tool arranged to operate on the margin of a sole so supported and fed, 60 an edge gage for guiding said sole, means

for adjusting said edge gage including a lever mounted to have a swinging adjusting movement and also arranged to have an additional movement, a power driven knife arranged to slash the stock adjacent to the 70 point of operation of said tool, and controlling means for said knife including a device lying beside the path of the swinging movement of said lever and arranged to be operated by said additional movement of said 75 lever.

6. A channeling machine having, in combination, a lip forming tool, means for supporting a sole and feeding it past said tool, a presser foot mounted to press the sole 80 against said support adjacent to the point of operation of said tool, a knife arranged to cut transversely into the sole at the rear side of said presser foot, and means for throwing said knife into and out of operation 85 during the continued operation of said feeding means.

7. A sole fitting machine having, in combination, a tool for operating on the marginal portion of the sole, a vertically movable 90 work support mounted to be raised or lowered relatively to the said tool for the insertion or removal of the work, a power driven knife arranged to slash the stock adjacent to the point of operation of said tool, 95 and controlling means for said knife including a manually operable device mounted to rise and fall with said work support.

8. A sole fitting machine having, in combination, a tool for operating on the marginal 100 portion of the sole, a sole support, a reciprocating sole feeding device operative to engage one face of the sole and feed it over said support and past said tool, and operating mechanism for said device comprising 105 a driven member movable in a fixed path and connected with said device to reciprocate it, a spring through which the movement of said member is transmitted to said device in one direction and adjustable means 110 for limiting the movement of said device so transmitted.

9. A sole fitting machine having, in combination, a tool, for operating on the marginal portion of the sole, a sole support, a sole feeding device operative to engage one face of the sole and feed it over said support and past said tool, and operating mechanism for said device comprising a driven member movable in a fixed path and connected 115 with said device to reciprocate it, a spring through which the movement of said member is transmitted in one direction to said device, a stop mounted for movement into and out of position to limit the movement 120 of said device transmitted by said spring, a spring tending to hold said stop out of said position, and manually operable means for moving said stop into said position.

10. A sole fitting machine having, in com- 130

5 combination, a tool for operating on the marginal portion of the sole, a sole support, a sole feeding device operative to engage one face of the sole and feed it over said support and past said tool, and operating mechanism for said device including a yoke through which reciprocating movement is imparted to the device, an eccentric block mounted to slide in said yoke in the direction of said reciprocating movement, a spring bearing against said block and tending to maintain it at one limit of its sliding movement, a driven eccentric member rotatable in said block, and a stop mounted 10 for movement into and out of the path of movement of said yoke and operative to limit the range of movement of said yoke.

11. A channeling machine having, in combination, means for engaging and supporting one side of a flat sole, a channeling tool on the other side of the sole, and a sole feeding device for advancing the sole, also opposite the sole supporting means but mounted independently of said tool, said device 20 having a part to bear on the extreme margin of the sole and hold it against the support while the sole is being channeled.

12. A channeling machine having, in combination, a sole supporting table, a lip forming tool immovable in the line of feed during the operation of the machine arranged to operate on a sole supported on the free side of said table, and a feeding device operative to engage said free side and feed the sole over the table to said tool, said device having a part constructed and positioned to bear on the extreme marginal portion of the sole and press it against the table during the feed.

13. A sole fitting machine having, in combination, a tool for operating on the marginal portion of the sole, a vertically movable table arranged to support a sole while said tool operates on it, means for holding 30 said table against downward movement while said tool is operating on the sole, an indicator, and operating mechanism for said indicator connected with said table and caused to function only by the lowering of the table to a sufficient extent to insert or remove a sole.

14. A sole fitting machine having, in combination, a tool for operating on the marginal portion of the sole, a vertically movable table arranged to support a sole while said tool operates on it, means for holding said table against downward movement while said tool is operating on the sole, an indicator, and operating mechanism for said indicator, connected with said table, constructed and arranged to transmit a registering movement to the indicator upon the first part of each downward movement of said table, but inoperative to transmit a further registering movement upon a continua-

tion of said downward movement of the table.

15. A sole fitting machine having, in combination, a tool for operating on the marginal portion of the sole, a work support 40 arranged to sustain a sole while said tool operates on it, said tool and support being mounted for relative movement to permit the introduction of a sole between them or its removal therefrom, an indicator, and operating mechanism for said indicator connected with said table constructed and arranged to transmit a registering movement to the indicator upon a relative movement of said support and tool of sufficient extent to 45 permit the removal or insertion of the work in the machine, said mechanism being ineffective to operate the indicator due to relative movements of the tool and work support to accommodate variations in the thickness of the sole.

16. A channeling machine having, in combination, a sole supporting table, a lip forming tool, an edge gage, and means bearing on the extreme margin of the sole in advance 50 and in the rear of the edge gage to press the sole firmly against the table.

17. A channeling machine having, in combination, a sole supporting table, a lip forming tool, an edge gage, a presser foot at the 55 rear of the edge gage bearing on the extreme margin of the sole, and a device for feeding the sole to said tool having a part to bear on the extreme margin of the sole in advance of the edge gage.

18. A sole fitting machine having, in combination, a sole fitting tool, a sole support, a reciprocating sole feeding device to advance the sole to said tool, and operating mechanism for said device comprising an eccentric and means, under the control of and operable by the operative while the machine is in operation, for nullifying more or less of the eccentric throw in one direction whereby the speed of operation may be 105 varied.

19. A sole fitting machine having, in combination, a sole fitting tool, a sole support, a reciprocating sole feeding device to advance the sole to said tool, a driven member 115 movable in a fixed path, and means normally held in inactive position but movable into active position while the machine is in operation, for varying the effective starting point of the driven member whereby more or less of its path of movement may be 120 utilized to vary the speed of operation.

20. A sole fitting machine having, in combination, a sole fitting tool, a sole support, a reciprocating sole feeding device to advance the sole to said tool, and operating mechanism for said device comprising a carrier therefor having a yoke, a block in said yoke, a cover plate for the open end of said yoke, a spring between said block and cover 130

plate, an actuator connected to said block, and means for variably limiting the movement of the carrier in the direction of the open end of its yoke.

5 21. A sole fitting machine having, in combination, knives for forming two parallel lips at the margin of the sole, a duplex knife arranged to straddle the between substance and slash the lip material of each lip trans-

10 versely, and means for operating said knife.

22. A sole fitting machine having, in combination, knives for forming two parallel lips at the margin of the sole, a device to feed the sole to said knives, and two additional knives for transversely slashing the stock in the path of said lip knives constructed and arranged to permit the sole feeding device to operate between them.

23. A sole fitting machine having, in combination, a sole fitting tool, a sole supporting table movable away from said tool to

remove the work, a shank for said table movably guided in the frame, an indicator, and indicator operating mechanism comprising a ratchet wheel for the registering mechanism, a pawl for the ratchet wheel, and a lever for operating said pawl connected to be actuated in a pawl-operating direction only by the movement of the table shank to a sufficient extent to draw the table away 30 from the tool far enough to insert or remove a sole.

24. In a machine of the character described, the combination with means for supporting and feeding a shoe sole and two 35 knives to form channel and edge lips in the margin of the sole, of a knife arranged to slash the lip material transversely, and means for throwing said knife into and out of operation at will during the continued operation of said feeding means.

ALBERT E. JOHNSON.
